UNITED STATES PATENT OFFICE.

WILLIAM C. FREEMAN, OF NASHVILLE, TENNESSEE.

SOUND-AMPLIFIER FOR PHONOGRAFS.

1,285,668.

Specification of Letters Patent. Patented Nov. 26, 1918.

Application filed January 21, 1918. Serial No. 213,002.

To all whom it may concern:

Be it known that I, WILLIAM C. FREEMAN, a citizen of the United States, residing at Nashville, in the county of Davidson and State of Tennessee, have invented new and useful Improvements in Sound-Amplifiers for Phonographs, of which the following is a specification.

This invention relates to sound amplifiers for phonographs and the like, and more particularly to phonographs of that kind commonly known as the cabinet type and wherein the sound chamber or amplifier is inclosed within the cabinet and is located below the turn-table for a record of the flat disk type.

Among the objects of my invention is to improve the construction of sound amplifiers of the kind referred to in the several particulars as will hereinafter more fully appear, and to provide, in particular, a sound chamber or amplifier of such a construction that will not only enhance the strength, volume, and quality of the sound conveyed thereto from the tone arm, but will also eliminate the abrasive sounds caused by the travel of the stylus over the record and also all such foreign noises as nasal sounds and the like, which have heretofore been rendered markedly audible when playing phonographs as heretofore made. Furthermore, with my improved sound chamber or amplifier it is possible when rendering a selection, whether instrumental or otherwise, to produce a tone as true and as natural as the tone of the selection when originally produced in the making of the master record.

In carrying out the objects of my invention, I provide in general a hollow sound chamber or amplifier of the tapered type, and provide within such chamber, adjacent the end communicating with the conduit of the tone arm, a plurality of oppositely disposed plates of glass or like sound-conducting material, so as to increase the strength of the tone of the sound conveyed to such chamber through the tone arm. In order to present the greatest possible amount of resonance and volume to the sound, I provide several metallic plates arranged opposite each other and located one on each side of said glass plates, and, furthermore, surround each of such plates with resilient material, such as rubber, which material serves to deflect the sound waves within the sound

box and neutralize the abrasive, nasal, and other foreign sounds likely to be produced in the playing of a record, to such an extent as to make the same not audible and thus completely eliminate the same.

The invention consists further in the matters hereinafter described and more particularly pointed out in the appended claims.

In the accompanying drawings—

Figure 1 is a vertical sectional view taken through the cabinet of a phonograph and showing therein, in elevation, a hollow sound chamber or amplifier constructed in accordance with my invention;

Fig. 2 is a view looking into said sound chamber or amplifier from the outer or larger end thereof, the cabinet and other parts of the phonograph being omitted for the sake of clearness of illustration;

Fig. 3 is a vertical sectional view taken on line 3—3 of Fig. 2;

Fig. 4 is a horizontal sectional view taken on line 4—4 of Fig. 1;

Figs. 5 and 6 are longitudinal sectional views taken on lines 5—5 and 6—6, respectively, of Fig. 10;

Figs. 7 and 8 are like views taken on lines 7—7 and 8—8, respectively, of Fig. 9;

Fig. 9 is a top plan view of one of the walls of the sound amplifier;

Fig. 10 is a like view of another of such walls; and

Fig. 11 is a vertical sectional view taken on line 11—11 of Fig. 3.

In Fig. 1 of the drawings, I have shown a hollow sound chamber or amplifier 10 constructed in accordance with my invention and installed in a phonograph of the cabinet type, the latter having a front wall 11, a rear wall 12, a top wall 13, side walls 13^a, and an interior partition wall 14, which separates the compartment in which the amplifier 10 is located from the compartment therebelow. Said sound amplifier 10 is made tubular in form, and in the example shown is substantially rectangular in cross-section. In addition, said amplifier is tapered lengthwise with both ends open, the larger end being the outer end thereof and opening outwardly through a grille 15 provided in said front wall 11. The inner or smaller end of said sound chamber or amplifier 10 abuts against the opposed end of a conduit or pipe 16 and opens therewith, as customary in

phonograph construction. The upper end of said pipe 16 communicates with a swinging tone arm 17 located above the top wall 13. Also above said top wall 13 is a turn-table 18, mounted on a vertical shaft or spindle 19 extending downwardly through said top wall and suitably connected with a motor (not shown) provided in the cabinet for rotating said turn-table, as customary in devices of this character. As usual in phonograph construction, the outer or swinging end of the arm 17 is provided with a reproducing stylus 20 adapted to travel over a record 21 when placed on said turn-table. So much of the construction described is provided generally in all phonographs of the type referred to, and forms no part of my present invention, but has merely been described and shown for the purpose of illustrating the manner in which my improved sound chamber or amplifier 10 is applied thereto.

Referring to my improved sound chamber or amplifier 10, the same comprises two aligned parts or sections 22 and 23, which parts when placed together in a phonograph cabinet or the like, form the complete sound chamber or amplifier, as clearly shown in Fig. 1. The section 22 is the forward one, and is positioned adjacent the grille 15, while the section 23 is the rearward one and extends between the forward section and the conduit 16. The sections are placed together in alinement, as shown, with their meeting ends abutting. The forward section 22 is made of wood, preferably red cypress, and comprises four connected walls, there being a top wall 24, a bottom wall 25, and two side walls 26, 26. Said walls are so arranged that the grain of the wood runs transversely across the amplifier 10, as clearly shown in Fig. 1. The rearward section 23 is also made of wood and comprises four connected walls, a top wall 27, a bottom wall 28, and two side walls 29, 29, all of such walls forming continuations of the corresponding walls of the forward section 22. The walls of the rearward section 23 are made of wood, the grain of which may run lengthwise of the sound amplifier, as clearly shown in Fig. 1. Applied against the inner face of each top and bottom wall 27, 28 of the rear section 23 is a flat metal plate 30, preferably made of iron and of a size less than that of the inner surface of such wall, as shown in Figs. 2, 4, 8, and 9. Said metal plate 30 has a uniform thickness throughout, and is centrally located with respect to the margin of the wall to which it is secured, as for instance by screws 31, 31. Surrounding the margin of said metal plate 30 is a strip of resilient material, such as rubber 32, which in the instance shown is made in one integral piece, but separate pieces of rubber 65 may be used if found desirable. The rubber

strip 32 is as wide as the distance between the spaced edges of the metal plate and the outer edges of the wall to which the latter is secured, and, furthermore, has a thickness equal to that of the metal plate 30, so that one is substantially flush with the other. The top and bottom walls 27, 28 are alike in construction, and when in a sound amplifier, the metal plates and surrounding rubber strips are directly opposite each other, as best shown in Figs. 2 and 3.

Applied against the inner face of each side wall 29, 29 is a flat plate of glass 33 or other like sound-conducting material. Said glass plate 33 is of a size less than that of the inner surface of said wall 29, and is centrally located with respect to the margin of said wall 29. In the example shown, said glass plate is secured to said wall 29 by an adhesive. Surrounding the edges of said glass plate 33 is a flat strip 34 made of the same kind of rubber or like material as the strip 32. When the walls 29 are in the sound amplifier, the plates of glass 33 are directly opposite each other, as shown in Figs. 2 and 4. The rubber strips 32, 34 are secured to the walls of the rear section 23 in any desired manner, as for instance by an adhesive. As shown in Fig. 11, the side walls 29, 29 of the rearward section have their upper and lower edges bearing against the top and bottom walls 27, 28, the rubber strips 32 on said top and bottom walls being made of such width as to extend across such edges of the side walls.

The object of making the sound chamber or amplifier 10 tapered is of course to amplify or magnify the sound conveyed into the same by the conduit 16 and tone arm 17, as usual in phonograph construction. Sound amplifiers as heretofore constructed have been made either all of metal or all of wood, or a combination of both, that is, the inner or main section being made of metal and the outer section being of wood or, in fact, a part of the cabinet structure. In any of these cases, there is produced and made audible, to a somewhat marked degree, through the sound amplifier, the abrasive sound produced by the travel of the stylus over a record in the operation of the machine. Moreover, there is also rendered audible, and quite distinctly so, the nasal like sounds of the voice when a song record is being played. Such nasal sounds seem to be produced to a more marked extent especially when playing those selections rendered by singers having high pitched voices, such as soprano, tenor, and the like. These objectionable sounds, or foreign noises as they may be called, are rendered audible even when playing the finest selections of the best artists on the more costly records, which is no doubt due to the fact that the sound amplifiers as heretofore constructed

have not been provided with means of a character adequate enough to eliminate all of such sounds, as is the case of a sound chamber or amplifier embodying the features of my invention. While the singer in rendering the original selection for the master record may have a voice entirely devoid of nasal and other objectionable sounds, yet when the records of such selection are 10 played on the phonographs as heretofore constructed, the nasal sounds are supplied to such an extent as to render a true reproduction of the selection objectionable to those having a fine musical instinct and 15 knowledge. It is one of the objects of my invention to overcome those objectionable sounds rendered audible by phonographs as heretofore constructed, and I have found that, by using a sound amplifier constructed 20 in accordance with my invention, a more perfect and natural tone is reproduced from the record, and all of the foreign noises, such as nasal and abrasive sounds heretofore noted, entirely eliminated. By producing 25 the rubber strips 33, 34 at the end of the sound chamber or amplifier 10, where the sound from the tone arm is first introduced or conveyed into said amplifier, the sound waves entering the same are deflected 30 by such resilient material and neutralized to such an extent as to suppress or render below audibility any of the nasal and abrasive as well as other foreign sounds likely to be produced during the playing of a record. 35 In other words, the sound is given complexion. The glass plates 33 are conductors of sound and serve to give the sound strength and thus enable the sound chamber or amplifier 10 to throw the sound the desired distance. In having the glass plates 40 arranged opposite each other, this feature is materially enhanced and rendered more effective, as the sound waves naturally are vibrated back and forth between said plates 45 and thus made stronger and given greater carrying qualities. The metal plates 30 serve to give the sound resonance and volume, or, as it might be said, fullness, such as produced by a bell. Taking my improved 50 sound chamber or amplifier 10 as a whole, the sound produced thereby is rendered more nearly to that of the natural and true tone of the voice or instrument, as the case may be, and yet eliminates the objectionable 55 foreign noise heretofore noticed in phonographs as heretofore constructed. With the section 22 of my sound amplifier made of red cypress and with the grain running as shown, the sound amplifier has such qualities as to more effectively accomplish the 60 objects of my invention, as I have found by experiments that such wood has the qualities referred to. The glass plates 33, 33 being arranged opposite each other in 65 the manner shown in my improved sound

chamber or amplifier 10, the sound when conveyed into the amplifier from the tone arm is projected against such glass plates, and the latter, being efficient producers of sound, serve to deflect or repel such sound waves from the glass plates, against which they initially strike. Said glass plates, having a smooth and continuous surface and being of an unyielding material, do not absorb any of the sound waves striking the 70 same, with the result that every sound wave that strikes the glass plates is repelled therefrom instantly, and in being vibrated back and forth between the oppositely disposed glass plates, it follows that the sound entering the sound chamber 10 is magnified to a much greater degree than when entering the sound chamber initially. Manifestly, by the provision of the glass plates it logically follows that the strength of the sound is 75 magnified to such an extent as to possess such carrying qualities that it may be heard at a considerable distance from the machine. The sound on entering the amplifier from the condutit 16 possesses a comparatively 80 high tension, and to relieve that I have provided the metal plates 30 arranged as shown. Such plates have the properties of absorbing sound to some extent and consequently 85 reduce the high tension of the sound upon 90 entering the sound chamber. The resilient or rubber strips, which I have placed around the edges of the glass and metal plates, serve to further relieve the high tension of the 95 sound being conveyed into the smaller end 100 of the sound chamber or amplifier 10, and also serve to blend the sound, with the result that, while the glass plates will magnify the sound and give it greater carrying qualities, yet the metallic and rubber plates of my 105 device will absorb or extract from the sound conveyed into the sound chamber 10 those nasal, abrasive, and such other foreign noises that are likely to be produced in the playing of a record. In other words, the provision of the glass, metallic, and resilient plates, arranged in accordance with my invention, will serve to balance the sound as it enters the sound chamber or amplifier 10 and thus produce a more natural and true 110 tone than has been accomplished with phonograph constructions as heretofore made and used. Other and further advantages incident to my invention will be apparent to those skilled in the art to which it has particular reference.

Although I have shown and described herein in detail one preferred form of sound box embodying the features of my invention, yet it is to be of course understood that the details of construction and arrangement of parts illustrated and described may be variously changed and modified without departing from the spirit and scope of my invention, and I do not wish to be restricted 125 130

or limited to the details of construction and arrangement of parts shown, except as pointed out in the appended claims.

I claim as my invention:

5. 1. A sound amplifier for phonographs and the like, comprising two oppositely disposed metallic plates, two plates of a sound-conducting material arranged on opposite sides of said metallic plates, and members made 10 of resilient material interposed between the opposed edges of said plates.
2. A sound amplifier for phonographs and the like, comprising two oppositely disposed metallic plates, two plates of a sound-conducting material arranged on opposite sides of said metallic plates, and rubber strips 15 interposed between the opposed edges of said plates.
3. A sound amplifier for phonographs and the like, comprising two oppositely disposed metallic plates, two plates of glass or the like, and strips made of a resilient material 20 interposed between the opposed edges of said plates.
25. 4. A sound amplifier for phonographs and the like, comprising a plurality of connected walls, at least one of said walls being provided with a plate of glass, and another of said walls being provided with a plate of metal, and strips of resilient material secured 30 to said walls and surrounding the edges of said plates.
5. A sound amplifier for phonographs and the like, comprising four connected walls, 35 two of said walls each being provided with a plate of glass and the remaining two of said walls each being provided with a metal plate, the walls having the glass plates being arranged opposite each other, and the 40 walls having the metal plates being arranged opposite each other, and rubber strips secured to each of said walls and surrounding the edges of said plates.
45. 6. A sound amplifier for phonographs and

the like, comprising two alined sections, one 45 forming a continuation of the other, one of said sections consisting of at least four connected walls, two of which each being provided with a glass plate and the two remaining walls each being provided with a 50 metal plate, the walls having the glass plates being arranged opposite each other and the walls having the metal plates being arranged opposite each other, and each of said walls being provided with a rubber strip 55 surrounding the edges of the plate secured thereto.

7. A sound amplifier for phonographs and the like, comprising two alined sections, one being made of wood, and the other section 60 consisting of four connected walls, two of which each being provided with a glass plate and the two remaining walls each being provided with a metal plate, the walls having the glass plates being arranged opposite each other and the walls having the metal plates being arranged opposite each other, and each of said walls having secured thereto a rubber strip surrounding the edges 65 of the plate secured to such wall. 70

8. A sound amplifier for phonographs and the like, comprising two alined sections, one being made of wood such as red cypress, and the other section comprising two oppositely disposed metallic plates, two plates 75 of sound-conducting material arranged on opposite sides of said metallic plates, and means made of resilient material interposed between the opposed edges of said plates.

In testimony that I claim the foregoing 80 as my invention, I affix my signature in the presence of two witnesses, this 15th day of January, A. D. 1918.

WILLIAM C. FREEMAN.
